UNITED STATES PATENT OFFICE.

CHARLES P. STEINMETZ, OF SCHENECTADY, NEW YORK, ASSIGNOR TO GENERAL ELECTRIC COMPANY, A CORPORATION OF NEW YORK.

ATTACHMENT FOR MERCURY-LAMPS.

940,209.

Specification of Letters Patent. Patented Nov. 16, 1909.

Application filed October 22, 1904. Serial No. 229,525.

To all whom it may concern:

Be it known that I, CHARLES P. STEINMETZ, a citizen of the United States, residing at Schenectady, in the county of Schenectady and State of New York, have invented certain new and useful Improvements in Attachments for Mercury-Lamps, of which the following is a specification.

This invention relates to means for increasing the reliability and safety of vapor electric lamps and similar translating devices.

While the invention is of general application, it is believed to be of particular value when used in connection with lamps operated in series on constant-current circuits.

It is well-known that constant-current generators of the type ordinarily used in series lighting systems do not "build up" readily on open circuit, and as mercury vapor lamps have a very high starting resistance difficulty has heretofore been encountered in operating these lamps on series circuits.

My invention comprises means whereby the generating machine may start on a low resistance circuit and whereby the high resistance lamps are not inserted into the circuit until the line current has attained a substantial value.

My invention further embraces a self-reducing resistance device in shunt with each lamp so that if the lamp fails to start when thrown in circuit, or if for any reason fails to carry its normal current, the resistance device will increase in conductivity and carry the normal line current for an indefinite period.

Figure 1 is a diagrammatic representation of my invention as applied to a mercury lamp; and Fig. 2 is a detail view of the preferred form of self-reducing resistance.

The mercury vapor lamp 1', which may be of ordinary form, comprises an upper electrode 2, a starting filament 3 of suitable resistance material, a mercury electrode 4, a magnetic plunger 5 floating in the mercury and in contact with the lower end of the filament 3, and a solenoid 6 adapted to control the movement of the plunger 5. When the lamp is thrown in circuit with the constant-current generator 1, the solenoid 6, which is connected in series with filament 3 at starting, draws down the plunger 5 from its po-

sition in contact with the lower end of filament 3, thus forming an incipient arc which starts the lamp. As the filament 3 has a very high resistance, the total resistance of all the lamps in circuit is often so high that the dynamo will not properly build up to normal current. To overcome this difficulty I provide the automatic cut-in device 7 shown in Fig. 1, which consists of the magnetizing coil 7' in series with the lamp and a movable armature 8 actuated by coil 7. In shunt with the lamp and in series with the coil 7' is a conductor 9 through which the starting current of the dynamo may pass before the mercury lamp is thrown in circuit. When the generating machine 1 is first started the armature 8 of the cut-in device is in a position to complete the circuit through the conductor 9 and as all the lamps 1², 1³, 1⁴, etc. of the circuit are similarly short-circuited the generator will readily build up on the low-resistance circuit thus formed. When the line current has attained substantially its normal value the current in coil 7' automatically lifts armature 8 and thus opens the circuit through conductor 9 and places the lamp directly in series with the line.

As previously stated, the initial resistance of the mercury lamp is very high so that at starting the voltage drop across the lamp may reach 150 to 200 volts, or even a higher value, and if for any reason the lamp fails to start a dangerously high potential may be produced at the lamp terminals due to the well known voltage characteristic of series dynamos, and not only is the lighting service interrupted but the insulation of the circuit is subjected to a severe strain. To overcome these difficulties, I provide a self-reducing resistance 10 in shunt with the lamp. This resistance may be of the form shown in Fig. 2 which comprises a metallic cylinder 11 threaded at each end and lined on the interior by a mica bushing 12. The self-reducing resistance material 13 consists preferably of a granular mixture of magnetite and mica held in place by two electrodes 14 and 15 which fit snugly within the mica lining. Sleeves 16 and 17 are provided respectively for the electrodes 14 and 15 and are screw-threaded on the outside of the pipe 11. Each sleeve is provided with hexagonal shoulders 18 and 18' adapted to form

a wrench seat. By screwing the two sleeves on the pipe 11 the electrodes 14 and 15 may be moved toward each other and so compress the resistance material 13. Annular washers 5 19 and 20 of mica or other suitable resistance material serve to insulate the electrodes 14 and 15 from their respective sleeves 16 and 17. If desired the resistance unit, instead of being built up as shown may consist 10 of a bar or rod formed by crushing the resistance material, mixing with it a suitable binder and baking the mixture to the desired form. When built in this way the mixture may contain magnetite and mica 15 as in the built-up unit or may consist of magnetite alone or mixed with other elements or compounds. These resistance units have a large negative temperature coefficient and so have the peculiar property of 20 decreasing in resistance from a very high value to a very low value when traversed by the line current and heated thereby. Furthermore, this reduction in resistance does not occur instantaneously, but only 25 after the lapse of several seconds which property is of great value when the resistance unit is used for the purpose here shown.

The usual form of cut-outs used with incandescent and arc lamps, such as film cut-outs, spark gaps, etc., is not adapted for 30 use with mercury vapor lamps for the following reasons: The starting resistance of the mercury lamp is very high and when the lamp is used on a constant-current circuit 35 the drop in voltage across the lamp at starting may be as high as 200 volts and for an instant even very much higher, although the running voltage of the lamp may be as low as 40 volts. This instantaneous high voltage 40 will break down a film cut-out or spark gap and thus permanently short-circuit the lamp, even though the lamp is in perfect condition. The resistance unit herein described will stand the starting voltage of 45 the lamp of 150 to 200 volts for several seconds without decreasing greatly in resistance and this interval is sufficiently long to allow the lamp to start even though the vacuum is not quite perfect. If at the 50 expiration of this time the lamp has not reached its normal condition of operation the resistance unit will rapidly decrease in resistance and finally carry substantially all the line current. This time limit of the resistance unit I consider of great importance 55 as it allows the lamp ample opportunity to start and at the same time operates with certainty to short-circuit the lamp, if after a suitable interval the lamp has not attained 60 its normal running condition. Not only does this resistance unit have a time limit but it has a time limit which is a function of the current carried by the resistance and hence of the voltage across the lamp. This allows 65 a slightly defective lamp ample time to start,

for if the voltage across the resistance unit is only slightly above normal the resistance will hold up even a minute or two and thus permit the lamp to start, but if at the end of this interval the lamp is not normal the resistance will cut it out entirely. On the other hand, if the lamp is broken or entirely open-circuited the excessive voltage at the terminals of the resistance unit will break it down in a very short interval of time. 70 This feature of a variable time limit is of value for the protection of a great variety of translating devices when used on constant-current circuits. The resistance unit has the advantages of being free from moving parts, 75 and of carrying no appreciable current when the lamp is operating under normal conditions, as well as many other advantages.

What I claim as new and desire to secure by Letters Patent of the United States, is,

1. In an electrical system, a series circuit, means for supplying current thereto, a vapor electric lamp, a conducting path in shunt with said lamp, automatic means for decreasing the current in said shunt path when the line current reaches a predetermined value, and a self-reducing resistance shunting said lamp.

2. The combination of an evacuated envelop, electrodes within said envelop for maintaining a current flow therethrough, starting means for initiating a current flow between said electrodes, said means having an appreciable time element, and a resistance permanently connected between said electrodes and having a negative temperature co-efficient.

3. The combination of a vapor electric apparatus having a high initial resistance and a relatively low running resistance, and a resistance unit in shunt with said lamp, having a negative temperature co-efficient, and adapted normally to carry no appreciable current.

4. In an electrical system, a series circuit, a plurality of lamps supplied by said circuit, said lamps having a high initial resistance and a relatively low running resistance and having an appreciable time interval at starting, and a self-reducing resistance in shunt with each of said lamps and capable of withstanding a high potential during the normal starting interval of a lamp, but adapted to break down if that interval is prolonged.

5. The combination of a mercury vapor lamp and a self-reducing resistance in shunt with said lamp, said resistance having an appreciable time limit.

6. The combination of a mercury vapor lamp and a self-reducing resistance in shunt with said lamp, said resistance having a variable time limit.

7. The combination of a mercury vapor lamp and a self-reducing resistance in shunt

with said lamp, said resistance having a negative temperature co-efficient and a variable time limit.

8. In an electrical system, the combination of a series circuit, a plurality of translating devices in said circuit, and a self-reducing resistance in shunt with each of said translating devices, said self-reducing resistances

having a negative temperature co-efficient and a variable time limit.

In witness whereof, I have hereunto set my hand this 19th day of October, 1904.

CHARLES P. STEINMETZ.
